R. Mallory & Co., Inc., Indianapolis, Ind., a
corporation of Delaware

Application August 1, 1936, Serial No. 93,809

12 Claims. (CL 200—15)

This invention relates to electric switches such as are used for changing circuit connections in radio sets and other electrical apparatus.

The switch of the present invention is of the type illustrated in U. S. Patent No. 1,975,247 issued October 2, 1934 to Paul G. Andres and Arthur Hall.

An object of the invention is to provide a switch of improved mechanical structure which is readily adaptable to a great variety of electrical circuits.

Another object of the invention is to provide a switch capable of use as a coil changing switch in long and short wave radio receiving sets.

Other objects of the invention will be apparent from the following description and accompanying drawings taken in connection with the appended claims.

The invention comprises the features of construction, combination of elements, arrangement of parts, and methods of manufacture and operation referred to above or which will be brought out and exemplified in the disclosure hereinafter set forth, including the illustrations in the drawings.

For a fuller understanding of the nature and objects of the invention as well as for specific fulfillment thereof, reference should be had to the following detailed description taken in connection with the accompanying drawings, in which:

Figure 1 is a longitudinal section through a gang type switch arranged according to the present invention;

Figure 2 is a section on the line 2—2 of Figure 1;

Figure 3 is a detail view, partly in section, showing features of the control shaft and indexing means;

Figure 4 is a section on the line 4—4 of Figure 1;

Figure 5 is a section on the line 5—5 of Figure 1;

Figure 6 is a section on the line 6—6 of Figure 1;

Figure 7 is a section on the line 7—7 of Figure 1;

Figure 8 is a detail view illustrating parts of a single rotor-stator assembly;

Figure 9 is a section on the line 9—9 of Figure 5; and

Figure 10 is a detail view illustrating the method of securing certain of the stator contacts to the base.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as

generic in their application to similar parts as the art will permit.

While gang type switches have been used heretofore the present invention provides improvements in construction which not only provide a more rigid, better aligned switch assembly but also enable a larger variety of circuit combinations to be obtained with a switch unit of a given size.

Referring to the drawings, the switch illustrated 10 comprises an index plate 20 and a plurality of stator discs 21, 22, 23 and 24 held in spaced aligned relationship by a pair of threaded rods 25 and 26 provided with sleeves 27 and 28 between each pair of discs for spacing them apart. 15

The control shaft 29 extends through the switch assembly. Shaft 29 is formed of two parts comprising a portion of circular cross-section 30 and a flat portion 31 secured together between index plate 20 and the first stator disc 21. Rotors 20 41, 42, 43 and 44 are mounted to turn in stator discs 21, 22, 23 and 24, respectively, under control of shaft 29.

An index arm 32 and a stop arm 33 are both mounted on shaft 29 to co-operate with index 25 plate 20. The index and stop arms are secured to the shaft 29 and shaft sections 30 and 31 are joined together in the following manner: Shaft 30, which is of circular cross section, is provided with an end 36 of slightly reduced diameter (as 30 seen most clearly in Figure 1) and a slot 34 is cut in the end of shaft 30 as indicated, slot 34 being adapted to receive the end of flat shaft 31. Shaft 31 is provided with a groove 35 on each side near its end. Index arm 32 which comprises an 35 S-shaped piece of spring metal having a central slot of such shape to receive the reduced end portion 36 of shaft 30 and the end of shaft 31 is then slipped over the end portion 36 so as to rest on the shoulder between portion 36 and the body of 40 shaft 30. Stop arm 33, comprising a piece of sheet metal stock also provided with a slot of the same shape, is slipped over the end 36 on top of index arm 32. Flat shaft 31 is then inserted in slot 34 and the central slots in arms 32 and 33. 45 It will be noted that when the shafts are thus assembled the end of portion 36 will partially cover groove 35 in shaft 31. The end of portion 36 is then deformed into groove 35 from both sides and is also spread out over the top surface of arm 50 33 thereby firmly uniting all of the parts into a rigid aligned assembly.

Index plate 20 is provided with a circular series of raised convex faces 37 stamped up from its surface to provide indexing projections. A pair 55

of stop lugs 38 are also stamped up from index plate 20 at positions determined by the requirements of the circuit in which the switch is used. Index arm 32 is provided at its two opposite ends with a pair of rollers 39 having pintles 40 which rest in recesses in the ends of arm 32 opposite the indexing portion of index plate 20. Stop arm 33 has its end bent at right angles toward plate 20 so as to engage stop lugs 38 on index plate 20.

10 Shaft 30 is mounted to turn in bushing 45 held in a central opening in index plate 20 by flanges 46 and 47 on the bushing. Index arm 32 is held under its spring tension against the index plate 20 by a split washer 146 fitted into a groove 147 cut in shaft 30.

15 The switch illustrated in the drawings has been shown with four different rotor-stator combinations for purposes of illustration. It will be obvious, however, that the combinations may be 20 varied as desired and that various other combinations are possible using the parts illustrated. It is also obvious that switches may be made according to the present invention having only one rotor-stator assembly or having any number of 25 such assemblies greater than one on the same shaft within the limits of practical operation. It will likewise be obvious that many of the parts are standard and interchangeable and can be used in a wide variety of combinations. The combinations 30 illustrated may be taken as examples of some of the more typical combinations required in radio receiving sets and the like.

35 The first rotor-stator assembly or switch section, comprising stator 21 and rotor 41, is illustrated in section in Figure 1 and one face view is illustrated in Figure 4. Details of the formation of the rotor and stator for this section, as well as for other sections, are illustrated in Figure 8.

40 Stator 21 comprises a disc stamped from a sheet of insulating material such as laminated Bakelite or other resin impregnated sheet material or molded resin material or ceramic material. The stator disc is of generally circular shape but is 45 provided with a pair of ears at the two opposite sides in which are punched a pair of holes 48 for receiving the rods 25 and 26. Disc 21 is also provided with a large central circular opening 49 for receiving the rotor 41. Surrounding opening 49 50 are a series of elongated arcuate openings or slots 50. The purpose of these slots is to reduce the amount of Bakelite between the conductive switch parts so as to provide an air dielectric where possible and thereby improve the high frequency characteristics of the switch. The disc 21 55 is also punched with a circular series of small rectangular holes 51 arranged in pairs for mounting the stator contacts.

60 The stator contacts 52 are secured to the stator disc 21 in the manner indicated in Figure 10. Each contact 52 is formed from a strip of sheet metal stamped and bent into the doubled form shown in Figure 10. The finished contact thereby 65 comprises a double portion 53 for a soldering lug, portion 53 having a hole 54 through which the end of the connecting wire may be inserted if desired before soldering. The central portion of each contact 52 comprises a generally rectangular mounting portion 55 in one arm of the contact, 70 the other arm of the contact resting against its surface. Portion 55 has a pair of opposed notches 155. The arms of the doubled contact terminate in a pair of contact fingers 56 and 57 provided with opposing convex contact faces 58 75 and 59, respectively, near their ends.

Each contact 52 is secured to the stator disc 21 by a U-shaped anchoring member 60 having arms 61 and 62. In mounting the contact arms 61 and 62 are inserted in holes 51 in the stator disc so that the mid-portion of member 60 rests against the opposite face of the stator disc from that on which contact 52 is to be mounted. Arms 61 and 62 then project up through holes 51 and fit into notches 155 in contact 52. The arms are then bent over the top face of portion 55 of the contact and the mid-portion of finger 57 thereby anchoring the contact firmly against the face of disc 21.

10 Rotor 41 comprises a pair of discs 41a and 41b of the form shown in Figure 8. The rotor discs are preferably formed of molded insulating material such as ceramic, isolantite, porcelain, molded Bakelite or other resin materials, resin-impregnated fibre, or the like. Rotor discs 41a and 41b are provided with central openings 63 for receiving flat shaft 31. The openings 63 are of the 20 same general shape as shaft 31 and provide sufficient clearance with the shaft to allow it to be inserted and removed from the rotor by moving axially but fit the shaft sufficiently close to prevent excessive play. Openings 63 are also arched 25 away from the shaft on one side, as indicated, to facilitate assembly. It will thus be noted that the rotor discs 41 can be turned under control of shaft 31 but can readily be assembled with the shaft or removed therefrom by axial displacement. The outer surface of discs 41a and 41b are each formed with radial ridges 64 defining individual contact positions. A hole 65 is provided in each position for riveting the contact shoes to the rotor. The diameter of the bodies 30 of discs 41a and 41b is only slightly less than the diameter of opening 49 in stator disc 21 and each rotor disc is provided with a flange 66 of slightly larger diameter than opening 49, this flange resting against the face of disc 21 when the section 40 is assembled. Upon assembly the two rotor discs are brought together on opposite sides of stator 21 and positioned in opening 49 with their adjacent faces in contact and the holes 65 in alignment. The two rotor discs and the rotor contacts are then riveted together by rivets 67 thereby 45 permanently securing the rotor for rotation in the stator disc. Discs 41a and 41b also have a series of recesses 68 on their inner faces opposite the individual contact positions for a purpose to 50 be described later.

55 The rotor contact shoes comprise stampings of sheet metal provided with riveting portions having radial edges of such dimensions as to fit into individual contact positions between ridges 64 on the rotor discs. The size and shape of the rotor contacts will depend on the circuit conditions to be fulfilled and the number of contact positions each contact must occupy. In general, each contact will comprise one or more tapered 60 portions having edges of such dimensions as to fit into the individual contact positions between ridges 64 on the rotor discs. The outer edges of the contacts normally lie on the arcs of circles having their common center at the center of the 65 rotor. Thus, for a single-position rotor contact the contact shoe may be substantially the shape of a sector of a circle (see contact 72 in Figure 5). For contacts which cover two or more positions at least two riveting portions will normally be provided. On such contacts one portion of the outer edge may, if desired, be of lesser radius than another portion thereof so as to provide selective 70 cooperation with certain stator contacts (see contact 70 in Figure 4). The edges of the contact 75

shoes slide between contact faces 58 and 59 of stator contacts 52 so as to make contact therewith.

With particular reference to Figures 1 and 4 it will be noted that rotor contact 69 occupies two adjacent positions on the rotor and that when the rotor is in the position shown the rotor contact 69 electrically connects stator contacts 52 and 52a. Rotor contact 10 occupies three rotor positions and it will be noted that its outer edge is one-third of one radius and two-thirds of a lesser radius. Stator contact 52b has longer contact fingers 56b and 57b than those on the other contacts and is thereby adapted to make contact with the portion of rotor contact 10 of reduced radius. Contacts 52c and 52d can only make contact with the portion of longer radius. Thus, with the rotor in the position shown contacts 52b and 52d are electrically connected by contact 10. If the rotor is rotated for one step in a clockwise manner (as seen in Figure 4) contacts 51b and 51c will be connected. Rotation for one step from the position shown in a counter-clockwise direction will open both circuits.

Referring to Figures 1 and 5 the rotor contact 72 occupies a single rotor position on one face of the rotor and rotor contact 73 occupies the corresponding position on the opposite face, the two contacts 72 and 73 being connected through the rotor by rivet 74. The stator contacts 52e and 52f, which make contact with rotor contacts 72 and 73, respectively, in the position illustrated, are mounted on opposite faces of stator base 22 with a single anchoring member 60. They are insulated from each other, however, by a rectangular sheet of insulating sheet material 75 interposed between arms 61 and 62 and stator contact 52e.

This is illustrated in detail in Figure 9. Sheet 75 may preferably have notched edges to receive arms 61 and 62 and the shank of contact 52e. Thus rotor contacts 72 and 73 and rivet 74 serve to connect stator contacts 52e and 52f when the rotor is in the position illustrated.

Rotor 42 also carries contacts 76 and 77, contact 76 occupying three rotor positions and having an outer edge of reduced radius and contact 77 occupying three rotor positions on the opposite face of the rotor, one of the positions being common to contacts 76 and 77. In this instance it is desired that contact 76 connect stator contacts 52g and 52h both on one face of the stator and that rotor contact 77 connect stator contacts 52i and 52j on the opposite face. In order to keep rotor contacts 76 and 77 electrically insulated from each other a pair of short rivets 78 and 79 are used for the common position having their heads disposed in recesses 68 in the rotor discs 42a and 42b. The other rivets 80 and 81 for contacts 76 and 77, respectively, are full length rivets similar to rivet 67.

In Figures 1, 6 and 7 are illustrated another arrangement of switch section. One face of the rotor, shown in Figure 6, carries a single position contact shoe 82 and a second contact shoe 83 which occupies all positions not occupied by contact 82. The opposite face of the rotor carries a contact shoe 84 (Fig. 7) forming a complete ring so as to occupy all positions. Contact 82 is connected to contact 84 through rivet 85. It is possible with this arrangement selectively to connect any one of stator contacts 52k, 52l, and 52m to stator contact 52n, the latter contact making contact with ring 84 and the remainder making selective contact with single position

rotor shoe 82. With contact 52k connected to contact 52n, as illustrated, the remaining stator contacts are connected together by rotor contact shoe 83, which may be grounded to the shaft 31, if desired.

While each rotor contact is shown riveted to the rotor at the end positions of the contact face it is not always necessary that the rivets be in these positions since the stiffness of the rotor contacts is normally sufficient to allow the rivets to be placed at intermediate positions.

With the rotor-stator arrangement provided by the present invention each rotor is definitely centered and located in its individual stator and does not depend on the shaft for support. In fact, the shaft is held centered by the rotors, each of which is, in effect a bearing for the shaft.

It will be obvious that a wide variety of circuit combinations are possible with the switch sections shown and that other contact combinations may readily be assembled from the standard parts illustrated and modifications thereof.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. An electric switch comprising a stator disc of insulating material having an opening therein and a rotor disposed in said opening, said rotor comprising a pair of discs secured together face to face, each of said discs having a flange on its peripheral edge, said flanges being located on opposite sides of said stator disc and extending out over the edge of said stator opening, whereby said flanges are adapted to retain said rotor and stator in assembled relation with said rotor rotatable in said stator, contacts on said stator and contacts on said rotor arranged so as to co-operate with said stator contacts.

2. An electric switch comprising a stator disc of insulating sheet material, an opening therein and a rotor mounted so as to turn in said opening, said rotor comprising a circular disc-shaped body portion of insulating material having a pair of integral flanges thereon resting against opposite faces of said stator disc, and co-operating rotor and stator contacts on said rotor and stator respectively.

3. An electric switch comprising a stator disc of insulating material, an opening therein and a rotor mounted so as to turn in said opening, said rotor comprising a pair of circular discs, means securing said discs together face-to-face in said opening, each of said discs having a flange resting against one face of said stator disc, and co-operating rotor and stator contacts on said rotor and stator, respectively.

4. An electric switch comprising a stator disc of insulating material having an opening therein, a rotor disc arranged so as to turn in said opening, a stator contact on said stator and a co-operating contact on said rotor, and means securing said rotor contact to said rotor disc, said means terminating within said rotor disc.

5. An electric switch comprising a stator disc of insulating material having an opening therein, a rotor disc arranged so as to turn in said opening, a stator contact on said stator and a co-operating rotor contact on said rotor, and means securing said rotor contact to said rotor disc, said means comprising a rivet having its head terminating within said rotor disc.

6. An electric switch comprising a stator disc of insulating material having an opening therein, a rotor disc arranged so as to turn in said opening, stator contacts on opposite faces of said stator, 5 rotor contacts on opposite faces of said rotor and aligned riveting means individual to said rotor contacts, each said means terminating within said rotor so as to allow a space between said means and retain said rotor contacts insulated from each other.
10. An electric switch comprising a stator disc of insulating material having an opening therein, a rotor arranged so as to turn in said opening, said rotor comprising a pair of discs of insulating material secured together face to face, a 5 stator contact on said stator and a cooperating contact on said rotor, and means securing said rotor contact to one of said rotor discs, said means terminating in the region between said rotor discs.
11. An electric switch comprising a stator disc of insulating material having an opening therein, a rotor arranged so as to turn in said opening, said rotor comprising a pair of discs of insulating material secured together face to face, a 15 stator contact on said stator and a cooperating rotor contact on said rotor, and means securing said rotor contact to one of said rotor discs, said means comprising a rivet having its head terminating between said rotor discs.
12. An electric switch comprising a stator disc of insulating material having an opening therein, a rotor arranged so as to turn in said opening, said rotor comprising a pair of rotor discs of insulating material secured together face to face, 25 stator contacts on opposite faces of said stator, rotor contacts on opposite faces of said rotor and aligned riveting means individual to said rotor contacts, each of said means terminating between said rotor discs so as to allow a space 30 between said means and retain said rotor contacts insulated from each other.
8. An electric switch comprising a stator disc of insulating material, a rotor disc of insulating material arranged so as to turn in said stator disc, and cooperating insulating flanges on said rotor disc arranged to hold said pair of discs in assembled relation.
9. An electric switch comprising a stator disc of insulating material, a rotor disc of insulating material arranged so as to turn in said stator disc, and continuous cooperating insulating flanges on said rotor disc arranged to hold said pair of discs in assembled relation.

HARRY C. HALL.
